(57) **CLAIM**

The ornamental design for an LED package, as shown and described.

DESCRIPTION

FIG. 1 is a side, top perspective view of an LED package of our new design;

FIG. 2 is a top view thereof; and,

FIG. 3 is a bottom view thereof.

The ornamental design, which is claimed, is shown in solid lines in the drawings. Any broken lines in the drawings are for illustrative purposes only and form no part of the claimed design.

1 Claim, 3 Drawing Sheets

FIG. 1

FIG. 2

FIG. 3
